COUNTERBALANCING DEVICE

Richard R. Bloss and Roy C. Pfeil, Columbus,
Ohio, assignors to The International Derrick &
Equipment Company, Columbus, Ohio, a cor-
poration of Ohio

Application February 14, 1927, Serial No. 167,924

8 Claims.

(Cl. 74—591)

Our invention relates to a counterbalancing device for attachment to cranks and has to do primarily with the provision of a novel form of counterbalance that is attached to, and works in conjunction with, the crank, rather than the band wheel or walking beam of an ordinary oil well drilling and pumping mechanism.

In our invention, certain features of adjustability have been provided to meet the normal variations in the weight of the suspended pumping or drilling mechanism and the oil or other fluid above the plunger. These features of adjustability are also calculated to obviate the jerky movements of the parts of the pumping mechanism and to provide a smooth and uniform operation throughout all cycles of such pumping or drilling operation.

The fact that our counterbalance is designed so as to be attached to and operate with the crank has a decided advantage over a band wheel or walking beam counterbalance. This advantage resides in the fact that the wear and tear on the band wheel and walking beam and the torsional stress on the crank-shaft, as produced by the ordinary type of band wheel or walking beam counterbalance, is eliminated.

Another important feature of our invention resides in the fact that we provide a plurality of weight members and means of adjusting the counterbalance with respect to its distance from the crank-shaft. The weight members may be attached to or detached from the counterbalance so as to obtain a greater or lesser counterbalancing effect since, by varying the mass of the weight members and the distance of the counterbalance from the crank-shaft, any desired counterbalancing effect may be obtained.

Another feature of our invention is the ease with which the counterbalance unit may be detached from the crank-shaft.

Various other advantageous features of our invention will appear from the detailed description hereinafter set forth and the preferred embodiment of our invention is shown in the accompanying drawings wherein similar characters of reference designate corresponding parts and wherein

Figure 1 is a front elevational detail view of the preferred embodiment of our invention.

Figure 2 is a side elevational view showing our invention attached to the crank-shaft and crank of an ordinary oil pumping or drilling mechanism.

Figure 3 is a perspective view of our invention showing its position with relation to the front jack post and crank-shaft of an ordinary oil pumping or drilling mechanism.

Figure 4 is a front elevational detail view of a modified form of our invention.

Figure 5 is a top plan view showing the sup-

plemental weights attached to the main counterbalance casting.

Referring to the several figures of the drawings, and, particularly, to Figure 3, a special crank is shown at 1 as being mounted upon and keyed to a shaft 2, which, in turn, operates in a jack post bearing 3 supported by a jack post 4.

The counterbalance unit 24 is carried by the rods 6, which rods connect the counterbalance casting 5 and the split bearing 7. The hub of the crank 1 is machined to a smaller diameter for the accommodation of the split bearing 7, the shoulders formed on the hub by this reduction in diameter providing a lateral bearing for the split bearing 7, which bearing serves to keep the counterbalance unit in alignment. The split bearing 7 embraces the machined portion of the crank 1 and the machined portion of the crank 1 rotates in the split bearing 7 only when the crank rotates and the counterbalance casting 5 is disengaged from the crank 1.

Slots 17 and 18 provide access to the bottom nuts of the rods 6, which rods 6 suspend the main counterbalance casting 5 from the split bearing 7. These rods 6 are threaded at their upper portions allowing the counterbalancing unit to be suspended at varying distances from the crank-shaft 2. Slots 10, in the main counterbalance casting 5, are designed to cooperate with this adjustment.

The main counterbalance casting 5 consists of a flange 12 cast integrally with the boss 11. Supplemental counterbalance weights 13 are provided in order to vary the weight of the counterbalance unit. These supplemental weight elements are so designed that they may be readily attached to or detached from the main counterbalancing casting 5 by means of the bolts 14.

The counterbalancing casting 5 is attached to the crank 1 by means of the bolts 15. Slots 10 in the main counterbalance casting 5 and open ended slots 16 in the end of the crank 1 permit the main counterbalance casting 5 and the crank 1 to be easily disengaged. Upon loosening the nuts of the bolts 15, these bolts may be moved downwardly in the slots 10 until they move out of the open ends of the slots 16 of the crank 1.

A washer 21 on each of the bolts 15 serves as a spacer between the counterbalancing casting 5 and the crank 1. This spacer provides a clearance between the counterbalancing casting 5 and the crank 1 so that, when these two units are disengaged, the crank may be operated independently of the balancing unit.

The means provided on the crank 1 for varying the length of stroke of the pump would also be effective to adjust the counterbalance with respect to the variations in weight of the suspended pumping or drilling mechanism and the oil or

- other fluid above the plunger. If the counterbalance were left in the position shown in Figure 3, and the pump were adjusted for a long stroke by means of the wrist pin 19 and the holes 20, as shown in Figure 3, the effect of the counterbalance unit 24 would be less than if the wrist pin 19 were placed in one of the upper holes 20, to produce a short stroke, and the counterbalance unit 24 left in the position shown in the figure.
- 10 In Figures 4 and 5 of the drawings, we have shown a modification of our invention. This modification differs from the counterbalance shown in Figures 1, 2, and 3 only in the shape of the various parts and in the fact that the counterbalance unit is equipped with a plurality of slots 10, whereby the counterbalance unit 5 may be attached to the crank in any one of several positions (see Figure 4). This makes possible the advancing or retarding of the center of gravity of the counterbalance weight in its relation to the crank. By advancing or retarding the counterweight, it is possible to synchronize the maximum turning movement of the crank counterweight with the maximum rod load.
- 15 Slots 27 provide access to the bottom nuts of the rods 6 which are supported in the split bearing carried by the hub of the crank arm for shifting the position of the counterbalance unit relative to the crank shaft. Supplemental weights 20 28 are provided to vary the weight of the counterbalance unit. These supplemental weight elements are so designed that they may be readily attached to or detached from the counterbalancing unit 25 by means of the bolts 14.
- 25 It will be clearly obvious that we have provided a counterbalance whereby any desired counterbalancing effect may be obtained either by predetermining the position of the counterbalance unit with respect to the crank-shaft, by the addition 30 or subtraction of supplemental weight elements to the main counterbalance casting or by adjusting the wrist pin along the crank arm obtaining a long or short stroke of the plunger.
- 35 Having thus described our invention, what we claim is:
- 40 1. In counterbalancing mechanism for well pumping apparatus, an attachment for a crank-shaft comprising a crank arm with open ended slots, a weight structure having elongated slots 45 in the face thereof, and fastening means slidable in said elongated slots into and out of cooperative relation with the open ended slots of said crank.
- 45 2. Attachment for the crank-shaft of oil well pumping mechanism comprising a pendulous weight structure having T-slots in its face, a crank having open ended slots and bolts slidable 50 in said T-shaped slots into and out of cooperative relation with the open ended slots of said crank.
- 55 3. In counterbalance mechanism for well pumping apparatus, an attachment for a crank-shaft comprising a crank arm, a weight structure having elongated slots in the face thereof, and fastening means slidable in said elongated slots, said fastening means being adapted to secure said 60 weight structure to said crank arm.
- 65 4. A counterbalance mechanism for well pumping apparatus embodying a counterbalance weight, an attachment for a crank shaft comprising a crank arm with its extremity provided 65 with open-ended slots into which bolts carried by the counterbalance weight may be inserted

by movement longitudinally of the crank arm towards the crank shaft to preclude rotation of the crank arm without the counterbalance weight.

5 5. A crank arm, a hub thereon, an auxiliary arm mounted adjacent said crank arm, a bearing divided transversely into sections, means holding the said sections together, weights on said auxiliary arm, and means engaging said arms together, the said sections of said bearings being adapted to be separated to disconnect said arms from each other.

10 6. An attachment for the crank arm of a pumping mechanism comprising a counterbalance weight structure, means connected to the crank shaft upon which said crank arm is mounted and to the counterbalance weight structure for suspending said counterbalance weight structure from the crank shaft, means for attaching said counterbalance weight structure to said crank arm at a point other than its point of suspension 15 from the crank shaft, said last two means being of such construction that said counterbalance weight structure may be so connected as to swing with said crank arm or may be so disconnected that said crank arm can rotate independently and continuously while the counterbalance weight remains stationary and while the said means for suspending the counterbalance weight structure is still connected to the crank shaft, said counterbalance attaching means comprising a plurality 20 of connecting means disposed at spaced points along said counterbalance weight structure to permit said crank arm to be readily connected to said counterbalance weight structure at different points along the counterbalance weight structure.

25 7. A counterbalance attachment for well pumping mechanism comprising, in combination with a crank arm supported on a crank shaft, a pendulous weight supported from the crank shaft 30 and so mounted that it may be attached to said crank arm, and means for connecting said pendulous weight to said crank arm in such a manner that it will rotate therewith as a unit, said means being of such construction that the said pendulous weight may be entirely disconnected from 40 said crank arm so that the crank arm can rotate independently and continuously while the said counterbalance weight remains stationary and while it is supported by said crank shaft.

45 8. An attachment for the crank arm of a pumping mechanism comprising a counterbalance weight structure, means connected to the crank shaft upon which said crank arm is mounted and to the counterbalance weight structure for suspending said counterbalance weight structure from the crank shaft, means other than the suspending means for attaching said counterbalance weight structure to said crank arm, said suspending means being of such a nature as to 55 permit movement of the counterbalance weight from a position in cooperative relation to the crank arm to a position in non-interfering relation with the crank arm in order to permit the crank arm to rotate independently and continuously while the counterbalance weight remains stationary and while the said suspending means is still connected to the crank shaft.
